ABSTRACT OF THE DISCLOSURE

An expansion and compression joint for a road surface layer comprises a metallic caisson formed by two facing channel members one sliding freely and transversely into the other, one or both channels having end plates, and resilient means between the channels. As protection means against pinching and creep of the ends of the resilient means, a small tongue extension of the end wall of the resilient means is inserted between the side wall of the resilient means and the bottom of a channel member supporting it. The resilient means may enclose an air chamber or encase a separate inflatable bladder. The protection means may also be reinforced or harder rubber caps.

The present invention relates to expansion and compression joints which are inserted between the slabs of concrete structures. These joints are used particularly for road surfaces to maintain the concrete slabs under compression and thus prevent fissures arising whilst permitting dimensional variations of the slabs due to shrinkage of the concrete or to expansions and contractions of the surface.

These joints are generally placed transversely across the road surface in the intervals separating adjacent slabs so as to exert a directional compression in the longitudinal direction of the surface.

In United States Patent No. 3,106,879, filed January 30, 1961 for Expansion and Compression Joint for Road Surfacing, there are described expansion and compression joints comprising resilient air chamber means such as an inflatable bladder contained in the interior of a metallic caisson constituted by two U-shaped metallic elements engaged one in the other. These two U-shaped elements can penetrate more or less deeply one into the other compressing the bladder so as to follow the expansions and contractions of the slabs. This patent relates more particularly to means for preventing the bladder from being pinched between the two U-shaped sections or from creep, under the effect of the inflation pressure, in the spaces comprised between the two sections. These means consist in providing bands of elastic material placed longitudinally in the interior angles of the larger of the two sections. These bands can be rigidly fixed to the bladder itself.

Experiment has shown that these longitudinal elastic bands effectively prevent the pinching and creep of the bladder over the whole length of the bladder but that risks of pinching and creep still exist at the two extremities of the bladder at the places where the caisson constituted by the two sections is closed by end plates joined to the ends of one of these sections. The interposition of rubber plates between the faces of the extremities of the bladder and the plates of the extremities of the caisson do not always eliminate these risks.

It is therefore an object of the invention, to protect the extremities of the bladder in order to eliminate more completely the risks of pinching and of creep of the blad-

2

der in its parts corresponding to the extremities of the metallic caisson which contain it.

This protection can be effected by extending each wall of the end of the bladder by a small rubber tongue turned between the bottom of one of the ridged sections constituting the metallic caisson and the side wall of the bladder resting on this bottom.

In all cases, the resilient air chamber means or bladder can be air tight and itself contain air under pressure or better, can be a non-impervious elastic envelope containing a separate inflatable air-chamber. In the last case the bladder at the reinforced end can be reduced to simple caps covering only the ends of the air-chamber to be protected.

The invention relates also to a process for the manufacture of bladders with reinforced ends characterised in that there is made separately a central body of the bladder by extrusion and parts of the reinforced ends by moulding and the central body and the reinforced ends are joined.

Several embodiments by way of non-limiting examples of the invention are described below with reference to the accompanying drawings in which:

FIGURE 1 is a view in transverse section of a joint in accordance with the present invention, between two slabs of concrete of a road surface, the plane of the section being taken in the central part of the joint so that the form of this transverse section can apply to various embodiments of the invention shown by the other figures,

FIGURE 2 is a view from above of a section along the horizontal plane *a—a* of FIGURE 1; and

FIGURE 3 is a perspective view showing the reinforced end of the bladder of FIGURE 2.

Referring now to FIGURE 1, it is seen that the assembly of the joint comprises a deformable metallic caisson constituted by two U-form sections 7 and 8, which can slide transversely one into the other. Inside this metallic caisson is placed an elastic bladder 13 in the form of a hollow beading. This elastic bladder contains an air chamber 14 inflatable by a valve situated preferably at an end of the joint.

In the mounted position the joint extends across the road between two adjacent slabs of concrete 2 and 3, which rest on the foundation 1 and is supported by the faces of the ends of these slabs by intermediary metallic plates 4 and 5.

The interior section 7 is engaged fairly deeply in the exterior section 8 but of course there is provided a sufficient play to enable the expansion of the slabs 2 and 3.

The bladder 13 comprises longitudinal lips 13₁ and 13₂ situated so as to be just placed in the interior angles set into exterior section 8, opposite the edges 7₁ of the wings of the interior section 7.

When the air chamber 14 is inflated, the lips 13₁, 13₂ of the elastic bladder assume their place in the reentrant angles of the section 8 and they substantially fill the free space comprised between the bottom of the section 8 and the edge 7₁ of the wings of these interior section 7. They avoid the bladder 13 having its wall folded back in the spaces and from being nipped between the two sections.

In the case of FIGURES 2 and 3, the ends of the bladder 13 are, according to the invention, reinforced by means of a rubber tongue 20, made in one piece with the bladder. This tongue 20 extends on one side the end wall 21 of the bladder 13 and it is folded back between the side wall of the bladder and the bottom of the interior section 7. It is sufficiently thick to form a shield preventing the bladder from being nipped or from creep in the clearance 22 comprised between the end plate 11 jointed at the end of the section 8 and the face of the end of the section 7 under the effect of the inflation pressure of the air chamber. The end of the small tongue 20 can be

tapered to ensure a progressive joining up of the superimposed walls.

When the bladder is used with an interior air chamber 14, the end wall 21 of the bladder is partly cut out by a slit 23 (FIGURE 3) enabling the introduction of the air chamber. When, on the other hand, the bladder 13 is used without an air chamber, this slit is omitted and the end wall 21 is hermetically joined to the body of the bladder.

Finally, the ends of these bladders can be further reinforced by using for their ends, rubber mixtures more resistant to stretching than that constituting the central body of the bladders.

When the bladder 13 is used as a protective envelope, for an interior air chamber 14, it has no need to be tight and can then be constituted by separate elements, namely a central part 13a, and end parts 13b, the latter being suitably reinforced. These various parts are simply closed around the air chamber. In a further embodiment the bladder can be narrowed at the single parts of the ends 13b, having the form of caps reinforced as described above and covering only the ends of the air chamber to protect it from creep and from pinching by the ends of the caisson.

When the bladder 13 is on the other hand, used in an air chamber and which must be tight, the parts 13a, and 13b, must then be joined for example by vulcanised joints.

In the two cases, there are advantageously used the process of manufacture consisting of forming the central body of the bladder by extrusion of a hollow beadng of the desired profile whilst the reinforced ends are constructed and moulded separately. The different parts are then joined along transverse junction lines 28 as indicated in FIGURE 2. The body being capable of being cut to a desired length in a section of great length, it is then easy to obtain bladders of appropriate dimensions for joints of different lengths.

It will be understood that the invention is not limited to the above embodiments from which one can conceive other variants of execution, combining different characteristics described.

I claim:

1. An expansion and compression joint for road surface layers and the like, comprising a metallic caisson

consisting of a pair of metal channel members of substantially the same length, one of said channel members being of smaller cross-section than the other and the channels facing each other with the flanges of the smaller section channel member fitting between those of the larger to provide for free sliding movement of the channel members towards and away from each other, and at least the larger channel member having end plates closing the inner space of the caisson, a pair of longitudinal ribs provided to extend between the end of the smaller channel flanges and the bottom of the larger channel member, inflatable resilient casing means enclosed in the caisson and in contacting relationship with the inner surfaces of said caisson, the end walls of said casing means engaging the end plates of the larger channel member and extended by a tongue inserted between the bottom of said smaller channel member and the side wall of the casing means supported against said bottom.

10 2. A joint according to claim 1, wherein said longitudinal ribs are unitary with the inflatable casing.

15 3. A joint according to claim 1, wherein said casing consists of a central body and end members in form of separate caps engaging said end plates.

20 4. A joint according to claim 1, including an inflatable tube enclosed in said casing.

25 5. A joint according to claim 2, wherein said casing consists of a central body and end members in the form of caps engaging said end plates.

30 6. A joint according to claim 2, including an inflatable tube enclosed in said casing.

7. A joint according to claim 3, including an inflatable tube enclosed in said casing.

35 8. A joint according to claim 5, including an inflatable tube enclosed in said casing.
